UNITED STATES PATENT OFFICE

JAMES E. ELKINGTON, OF SAN FRANCISCO, CALIFORNIA

DISHWASHING MACHINE

Application filed May 27, 1930. Serial No. 456,158.

This invention relates to dish washing machines, in which dishes or other articles may be cleansed by mechanical application of a cleansing fluid.

5 It is an object of the invention to construct a water sprayer for a dish washing machine in such a manner that the cleansing fluid will be circulated from the receptacle of the dish washing machine to a nozzle to be discharged, 10 under pressure, upon the dishes or other articles in a wide, steady stream, so that the dishes or articles are thereby effectively cleaned in a short time.

Another object of the invention is to provide a housing on a side wall of the receptacle of a dish washing machine, which housing has an inlet at the bottom of the receptacle and an outlet nozzle at the upper end thereof, to discharge the cleansing fluid into 20 the interior of the receptacle, the said fluid being recirculated from the receptacle by an impeller in the said housing inlet; means being provided on the outside of said receptacle wall to drive the said impeller; and means 25 of connection being arranged between the housing and the driving means in such manner as to securely attach both to the said receptacle wall.

Other objects and advantages are to provide a dish washing machine that will be superior in point of simplicity, inexpensiveness of construction, positiveness of operation, and facility and convenience in use and general efficiency.

35 In this specification and the annexed drawing, the invention is illustrated in the form considered to be the best, but it is to be understood that the invention is not limited to such form, because it may be embodied in 40 other forms; and it is also to be understood that in and by the claims following the description, it is desired to cover the invention in whatsoever form it may be embodied.

The invention is clearly illustrated in the 45 accompanying drawing wherein,

Fig. 1 is a vertical sectional view of an end of the dish washing machine, showing the sprayer constructed in accordance with my invention.

50 Fig. 2 is a vertical sectional view of the

sprayer in the dish washing machine, showing another form of mounting of the sprayer housing; and

Fig. 3 is a front view of the sprayer on the side wall of a dish washing machine.

In carrying out my invention, I make use of a receptacle 6 of a dish washing machine, in which dishes or other articles to be washed are held. Adjacent a vertical side wall 7 of the receptacle 6 is disposed a combined pump and sprayer housing 8. The lower end of the housing 8 adjacent the bottom 9 of the receptacle 6 is formed into a pump housing 11, the inlet 12 of which extends at right angles to the side wall 7. From the pump housing 11 the housing 8 extends upwardly forming a discharge chamber, the width of which is gradually increased toward the upper end thereof, as shown in Fig. 3. The front and rear walls 10 of the housing 8 are 60 parallel with each other and with the side wall 7.

The upper end of the housing 8 is curved toward the interior of the receptacle 6 and is gradually reduced in height, to form an 73 elongated, tapering nozzle 13, discharging downwardly and substantially diagonally into the interior of the receptacle 6, directing the cleansing fluid onto the dishes or other articles in the machine.

In the inlet 12 is disposed an impeller 14 of a pump, mounted on the end of a drive shaft 16, which extends thru the side wall 7 and is connected to an electric motor 17, whereby it is rotated to drive the impeller 14. The motor 17 is outside of the side wall 7.

The housing 8 and the motor 17 are mounted on the side wall 7 by means of connections common to both, which do not include any screws, bolts or other similar fastening means. From the housing 8 protrudes an exteriorly threaded member 18 which snugly fits in an aperture 19 in said side wall 7. This member 18 may be an integral part of the housing 8, as in Fig. 1, or it may be threadedly secured into the rear wall 10 of the housing 8, as at 21 in Fig. 2.

A bracket 22 on which the motor 17 is mounted in the usual manner, has an inter-

nally threaded base 23 which is screwed upon the external thread of the member 18 or 21. It is to be noted that the base 23 bears tightly against the outer face of the wall 7, and it urges the rear wall 10 of the housing 8 into tight contact with the inner face of said wall 7. In this manner the housing 8 and the motor 17 are secured on each other and are also securely mounted on the wall 7 10 therebetween, without the use of screws, bolts, or rivets and the like. The afore-described mounting arrangement also greatly facilitates the removal of the motor 17 and of the housing 8 from the receptacle 6.

15 The shaft 16 extends thru the member 18. In order to prevent the escapement of cleansing fluid past the shaft 16, a packing gland 24 is secured in the outer end of the member 18 and of the member 21.

20 In operation the housing 8 is so disposed in said receptacle 6 that the inlet 12 is located below the fluid level in the receptacle 6. The rotation of the impeller 14 pumps the fluid from the receptacle 6 and forces the 25 fluid upwardly and out thru the nozzle 13, which latter discharges the fluid onto the dishes in the receptacle 6, in a wide, continuous, steady stream. Thus the cleansing fluid contained in the receptacle 6 is continuously recirculated and the dishes or other articles are washed thoroughly.

Having thus described this invention, what I claim and desire to secure by Letters Patent is:

35 1. In a dish washing machine, a receptacle to hold dishes to be washed therein, a combined pump and spray housing disposed adjacent a wall of the receptacle, a rotary pump in the end of the housing adjacent the 40 bottom of the receptacle, a diagonally downwardly directed nozzle on the upper end of the housing; means outside of said wall of the receptacle to drive the said rotary pump; means of connection between the housing 45 and the driving means, extending thru the said wall to mount both the housing and the driving means on said wall, said means of connection comprising a threaded member extending from the housing and thru said 50 wall, a bracket on the outside of the wall threadedly engaging said member to bear against the outer face of the said wall and to draw said housing against the inner face of said wall, said driving means being mounted 55 on said bracket.

2. In a dish washing machine, a receptacle to hold dishes to be washed therein; a housing in the receptacle disposed alongside a side wall thereof; a threaded member extending from the said housing and thru said side wall; a driving mechanism outside of said receptacle, a supporting element on which the driving mechanism is mounted, being threadedly secured on said member to 65 bear against the outside face of said side

wall to draw the housing against the inner face of the side wall thereby to secure the same in place, a drive shaft of said driving mechanism extending thru said threaded member into the end of the said housing; an inlet in said housing adjacent the bottom of the receptacle; an impeller blade in said inlet being mounted on the end of said driving shaft to pump fluid from the receptacle into and thru said housing; and a nozzle on 70 the other end of said housing to discharge the fluid directed to the interior of said receptacle.

3. In a dish washing machine the combination with a receptacle in which the dishes are washed, of an elongated nozzle inside of the receptacle extending alongside a wall of the latter from below to above the water level in said receptacle, said nozzle having an intake below the water level and a downwardly inclined outlet at the end thereof, rotary means in the intake to force the water upwardly and out through said outlet, driving means for said rotary means outside of said wall, said wall having an opening therein, an element protruding from said nozzle at right angles to its longitudinal axis and extending through said opening, and a mounting for said driving means detachably mounted on the portion of said element outside of said wall so as to draw said nozzle against the inner face of said wall.

4. Means of connection for a nozzle and a pump driving means in a dish washing receptacle having an opening on a side thereof, comprising an element extending from the outside of the nozzle substantially at right angles to the latter and protruding through said opening, the protruding portion of said element being externally threaded, a drive shaft journaled in said element, a pump on the inner end of said shaft, a driving mechanism on the outer end of the shaft, and a support for said driving mechanism threadedly engaged with said protruding portion of said element to draw the nozzle against the receptacle wall and seal said opening.

In testimony whereof, I have hereunto set my hand at San Francisco, California, this 23d day of May, 1930.

JAMES E. ELKINGTON.
